AUTOMOTIVE VEHICLE LICENSE TAG

Erasmus J. Sigler, Delmar, N. Y., assignor of ten
per cent to Arthur J. Bellinger, St. Johnsville,
N. Y.

Application November 3, 1941, Serial No. 417,699

1 Claim. (Cl. 40—125)

My invention relates to license tags for automotive vehicles, and has among its objects and advantages the provision of an improved tag of the so-called permanent type, wherein novel means is provided for attachment to the plate for indicating the year for which its use is authorized by payment of an annual registration fee.

In the accompanying drawing:

Figure 1 is a face view of a license tag in accordance with my invention;

Figure 2 is an enlarged sectional view taken along the line 2—2 of Figure 1;

Figure 3 is a rear elevational view of the invention;

Figure 4 is a face view of a modified form;

Figure 5 is a sectional view along the line 5—5 of Figure 4; and

Figure 6 is a fragmentary view of the structure of Figures 4 and 5.

In the embodiment selected for illustration, I make use of a license tag 10 of conventional size and construction. The usual license number 12 occupies the greater area of the tag. State identifying indicia 14 are also provided. The year for which the tag is authorized is indicated at 16, which indicia are preferably formed by embossing the material of the plate, as by stamping, throughout the outlines of the respective digits.

In accordance with my invention, one tag will serve for a period of ten years running from zero through nine through replacement of a digit plate 18. Plate 18 has an area slightly larger than the digit 20 and the plate 10 is depressed at 22 for the reception of the digit plate to bring the latter flush with the front face of the license tag. The license number 12 is duplicated in miniature at 24, which duplication is preferably struck from the tag 10 so as to project beyond the front face of the tag. Digit plate 18 is also provided with a duplication of the license number 12 in miniature, as at 26, which duplication is stamped in the digit plate, so as to have interfitting engagement with the distortions therein representing the duplication 24 in the tag 20. Thus the digit plate 18 will lie face to face with the depressed area 22 in the tag 10.

A digit plate 18 is issued each year, which plate is provided with the successive last digits in the respective years for which the digit plates are issued. Since each digit plate 18 is provided with a duplicate license number, the digit plates may be used only on the original plates for which they are issued. This prevents the digit plates from being appropriated for use on license tags other than those for which they are issued.

The digit 20 is preferably raised from the plane of the plate 18. In raising the license duplication 24 to have interfitting engagement with the license duplication 26, the digit plate 18 will register only when used on the original plate for which it is issued. In other words, a digit plate 18 will lie flush with the license tag 10 only when it carries the miniature license number of the plate for which it is issued. This feature provides a mismatched appearance when the wrong digit plate is employed so as to provide an unbalanced arrangement of the parts unless the proper digit plate is employed on the original license tag.

Digit plate 18 is provided with a plurality of right angular ears 28 passing snugly through slots 30 in the license tag 10. Each ear is partially severed crosswise, as at 32, to provide shoulders engaging the back face of the license tag when the ears are given a slight twist. An irregularly-shaped rib 34 is stamped in the license tag 10, and the digit plate 18 is also provided with a similarly shaped distortion 36 having interfitting engagement with the rib 34. Rib 34 also functions to improperly position the digit plate 18 on the license tag 10 unless the digit plate and the tag are provided with interfitting distortions. Thus the digit plate is rendered more difficult to duplicate.

In Figures 4 and 5, the digit plate 38 is provided with perforations 40 constituting outlines of the elements of the license number of the tag. The tag 42 has its miniature license number stamped therein, as at 44. The deformations 44 fit snugly in the perforations 40 to bring the digit plate 38 into face to face engagement with the depressed area 46 of the original license tag when the digit plate carries the license number in miniature corresponding to the number of the license tag for which it is issued. Digit plate 38 is secured to the tag 42 by ears 48 corresponding to the ears 28.

Slots 50 are provided in the digit plate 38 for the reception of correspondingly shaped ribs 52 stamped in the tag 42, which ribs correspond to the rib 34. Thus the digit plate 38 will seat properly only when it is perforated in accordance with the miniature license number distortions 44 and when provided with slots 50 which accommodate the ribs 52 stamped in the tag 42 at the time of manufacture.

The present invention provides a license plate which may be employed for a period of years through mere substitution of a digit plate. The digit plate is relatively small in size so as to procure a large saving in material as well as

costs incident to the manufacture of original tags for short term use.

Without further elaboration, the foregoing will so fully illustrate my invention, that others may, by applying current knowledge, readily adapted the same for use under various conditions of service.

I claim:

In a license tag having vehicle identification characters and a series of year identification characters, a digit plate having a character comprising one of said series of year identification characters, said digit plate being provided with a miniature duplication of said vehicle identifica-

tion characters, means detachably connecting the digit plate with said license tag, said vehicle identification characters in miniature being struck from said digit plate, and a miniature duplication of said vehicle identification characters struck from said license tag for interfitting engagement with the vehicle identification characters in the digit plate to bring the digit plate into predetermined positional relationship with the license tag only when the vehicle identification characters in miniature in the respective license tag and the digit plate are identical.

ERASMUS J. SIGLER.
